UNITED STATES PATENT OFFICE.

ROBERT C. SCHENCK, OF DAYTON, OHIO.

DESIGN FOR A HAND-WHEEL RIM.

SPECIFICATION forming part of Design No. 24,015, dated February 5, 1895.

Application filed November 28, 1894. Serial No. 530,277. Term of patent 14 years.

To all whom it may concern:

Be it known that I, ROBERT C. SCHENCK, a citizen of the United States, residing at Dayton, in the county of Montgomery and State 5 of Ohio, have invented and produced a new and original Design for Hand-Wheel Rims, of which the following is a specification, reference being had to the accompanying drawings, showing the same.

10 In the drawings Figure 1 is a plan view of my hand wheel rim, and Fig. 2 is a side elevation of the same.

The leading feature of my design consists 15 in the circular rim provided with oblong slots through it from top to bottom, said slots extending, with separating partitions, entirely around said rim, thus producing a novel and pleasing appearance, both when the rim is

viewed in plan or in side elevation, the slots giving to the top and bottom sides of the rim, 20 when seen in elevation, a corrugated appearance, as shown in Fig. 2.

A is the rim and α the oblong slots formed through it from top to bottom and extending, with separating partitions b , entirely around 25 said rim, thus presenting to the eye a pleasing appearance, when viewed either in plan or in side elevation.

Having thus described my design, what I claim is—

The design for the rim of hand wheels, substantially as shown and described.

ROBERT C. SCHENCK.
